UNITED STATES PATENT OFFICE.

HENRY M. CRANE, OF NEW YORK, N. Y.

DESIGN FOR AN AUTOMOBILE-RADIATOR.

47,152.

Specification for Design.

Patented Mar. 30, 1915.

Application filed December 12, 1914. Serial No. 876,987. Term of patent 14 years.

To all whom it may concern:

Be it known that I, HENRY M. CRANE, a citizen of the United States, residing in the borough of Manhattan, city, county, and State of New York, have invented a new, original, and ornamental Design for Automobile-Radiators, of which the following is a specification, reference being had to the accompanying drawing, forming part thereof.

Figure 1 is a top plan view; Fig. 2 is a

front elevation; and Fig. 3 is a side view of an automobile radiator showing my new design.

I claim:

The ornamental design for an automobile radiator, as shown.

HENRY M. CRANE.
